UNITED STATES PATENT OFFICE.

LESTER K. ALDRICH, OF SIDNEY, OHIO.

FEEDER.

Application filed November 30, 1923. Serial No. 677,721.

To all whom it may concern:

Be it known that I, LESTER K. ALDRICH, a citizen of the United States of America, and a resident of Sidney, in the county of Shelby 5 and State of Ohio, have invented a new and useful Improvement in a Feeder, of which the following is a specification.

An object of my invention provides an automatic feeder for sheet material and the 10 like, that is readily adaptable to operation upon sheet material of various thicknesses and stiffnesses, and is simple in construction and efficient in operation.

Another object of my invention is to provide 15 a device of the type described that is positive in its action of separating the sheets, preparatory to feeding of the sheets.

These and other objects are attained by the means described herein and disclosed by 20 the accompanying drawing, in which,

Fig. 1 is a front elevation of the device embodying my invention.

Fig. 2 is a side elevation of the device, showing Fig. 1.

Fig. 3 is an enlarged sectional view on line 3—3 of Fig. 2.

Fig. 4 is a plan view of the device shown in Fig. 2.

Fig. 5 is a rear elevation of the device 30 shown in Fig. 1.

Fig. 6 is an enlarged sectional view on line 6—6 of Fig. 1.

Fig. 7 is a sectional view of line 7—7 of Fig. 6.

Fig. 8 is a fragmental sectional view on line 8—8 of Fig. 5.

Fig. 9 is an enlarged fragmental view of parts shown in Fig. 2.

Fig. 10 is an enlarged plan view of an air 40 valve forming a detail of my invention.

The device of my invention comprises a frame 9 of a substantially rectangular horizontal cross section. The frame may comprise suitable sides 10 and 11, connected by cross bars 12 and the like. A vertically reciprocal table 13 is provided for supporting a stack of sheets 14, that are to be fed. The table is fed upwardly for advancing the stack 14 toward a nozzle 66, that is employed for removing individual sheets from the stack and feeding the individual sheets from the device. Any suitable means may be employed for advancing the stack 14. As shown herein said advancing means comprises a shaft 16 supported by the side 10 and extending rearwardly of the machine.

The shaft 16 carries a suitable hand wheel 17 and a worm 18. The worm 18 drives a worm wheel 19, mounted on a shaft 20, which shaft 20 carries a sprocket 21. A 60 chain 22 extends about the sprocket and supports at its one end, the table 13 and carries at its other end, a weight or counterbalance 23. An automatic advancing means is provided for the table 13. This automatic advancing means comprises a ratchet wheel 24, mounted on the shaft 16 and engaging a pawl 25, carried by the ratchet plate 26, mounted for oscillation on shaft 16. The ratchet plate 26 extends transversely of the frame 9, and is weighted at its inner end, as shown at 27, and carries a headed pin 28 at its other end, that is received in an elongated slot 29, formed in a link 30, depending from said ratchet plate. 70 From the foregoing it will be apparent that the weight 27 serves to move the ratchet plate, as shown in Fig. 3, in a counterclockwise direction, while the upper end of the wall of the slot 29 limits such counterclockwise movement of the ratchet plate. The lower end of the link 30, is pivotally connected to the forward end of an arm 31. The arm 31 may be actuated about its pivotal mounting 32 on the frame, in any suitable manner, for actuating the link 30. The frame carries adjacent the weighted end of the ratchet plate, a limiting means controlling the rotation of the shaft 16 by the ratchet mechanism. This limiting means 80 comprises a pivotally mounted bracket 33 provided with a finger 34 for engagement upon the upper surface 35 of the stack 14, and with a second finger 36 that may assume a position below the weight 27 for receiving the weight 27 and precluding the ratchet plate 26 from movement although the link 30 may reciprocate relative to said ratchet plate. From the foregoing it will be apparent that the movement of the link 30 will 90 have no effect on the advancing of the stack 14, unless the finger 36 is moved to the left of the weight 27, as shown in Fig. 3.

The arm 31 carries an upwardly projecting extension 37 carrying a rearwardly extending finger 38 and upon which finger is mounted a roller 39. The roller is contained within a way 40, formed in the cam 41. From the foregoing it will be apparent that the movement of the cam serves to actuate the arm 31 and various mechanisms connected to said arm. The cam in turn is 100 105 110

actuated from the motor 42 by way of belts 43 and 44, shafts 45 and 46, pulleys 47 and 48 and 49 and crank 50 carried by shaft 46 and pivotally engaging one end of a link 51. The other end of the link 51 is pivotally connected with the cam 41.

The shaft 45 is associated with a compressor that receives air by way of the pipe 52, whereby there is a tendency toward a 10 vacuum within the pipe 52. The air under pressure is directed into tank 53 by way of pipe connections 54. The tank 53 discharges by way of pipe 55. A valve 56 is controlled by the rear end of the arm 31 15 whereby to modify the degree of the vacuum tendency within the pipe 52. The valve 56 comprises a shutter 57 that is mounted by means of a pivot 58 upon the block 59 with which the bore of the pipe 52 communicates. 20 The block is provided with a port 60 for which the shutter serves as a closure. The rear end of the shutter 57 carries a pin 61 that is disposed within an elongated aperture 62 formed in the upper end of an up- 25 right extension 63, formed on the rear end of the arm 31. The shutter is practically balanced on its pivot 58 and is actuated in opposite directions by the wall of the aperture 62 and the depending extension 710 on 30 the arm 71. The upper end of the pipe 52 carries a cap 64 that serves as a valve, for modifying the suction or vacuum tendency within the pipe 52. The purpose thereof 35 will be explained hereafter. The pipe 52 communicates by way of a hose 65 with an oscillating nozzle 66, forming part of the pick up device for picking up individual sheets from the stack 14. The nozzle 66 is fixedly mounted upon a shaft 67 extending 40 transversely and at the top of the frame. The shaft is supported by brackets 68 and 69 mounted upon a shaft 70. The shaft 70 is rotatably supported by the sides 10 and 11. A roller arm 71 is fixedly mounted at 45 one end of the shaft 70 and carries a roller 72 that engages the cam 41. From the foregoing it will be apparent that as the roller carrying the end of the arm 71 is raised and lowered, the brackets 68 and 69 will 50 raise and lower the shaft 67 together with the nozzle 66. It should be observed that when the nozzle is in position to pick up a sheet from the stack 14, for example as shown in Fig. 2, the shaft 67 is slightly below the shaft 70, consequently, when the shaft 67 is moved upwardly, the said shaft also moves slightly forward of the frame, and this slight forward movement is used 55 for a purpose that will be explained hereafter. It is essential that this slight movement be understood in order that the operation of the device be fully appreciated. The shaft 67 is rotatably supported by the brackets 68 and 69 and has fixedly mounted at its 60 one end, a crank arm 73 that is pivotally 65 connected with a link 74. The link 74 has a pivotal mounting upon the upper end of the extension 37. From the foregoing it will be apparent that the nozzle may have imparted to it, both an oscillating motion about the 70 shaft 67 and an oscillating motion about the 75 shaft 70. By reference to Figs. 6 and 7, it will be apparent that the nozzle 66 is provided with a plurality of suction mouths 75, 76, 77 and 78. It is preferable to provide 80 a small rib 79 at the surface of said mouths to avoid distortion of the sheets. The several mouths communicate by way of ducts or passages formed in the nozzle 66 with ports 80, 81, 82 and 83 in the side of the 85 nozzle. The ports 80 to 83 inclusive may be brought into communication with the hose 65 for employing the suction or air pressure, resultant from the action of the compressor, for removing the upper sheet 90 from the stack 14 by means of the nozzle. The end 84 of the hose 65 is connected with a tubular stem 85, a block 86 that engages the side of nozzle 66. The block 86 has a bore 87 that registers with a bore formed 95 in the tube 85 and that may register with the several ports 80, 81, 82 and 83. The stem 85 is supported by a bracket 88 carried by a shaft 70 and against which bracket, a spring 89 mounted upon shaft 70 abuts. In 100 this way the block 86 is held in yielding engagement upon the side of the nozzle 66. The bracket 88 may be secured to the shaft 70 in any suitable manner, such as by a set screw and the like.

At the rear of the machine, the stack of sheets 14 abut a safety stop 90 that may be mounted upon the frame in any suitable manner and may be adjustable with the frame. The upper end of the safety stop 105 is angular and extends upwardly and rearwardly. In the normal operation of my device the lower end of said angular extension of the safety stop is at some distance above the normal upper level of the sheets 110 14. To the rear of the inclined upper edge of the safety stop 90 are disposed rollers 91 and 92 for receiving a sheet and passing same from the device. These rollers may be mounted in any suitable manner and may be driven in any suitable manner. For example, as shown herein, the roller 92 is supported from the frame by brackets 93 mounted upon shaft 94 extending transversely of the device. The roller 91 is mounted upon a shaft 95 having bearings upon the sides 10 and 11 and driven from the shaft 46 by a belt 96. Adjacent the safety stop 90 are disposed air discharge nozzles 97 and 98 that may be adjusted about a vertical axis and that may also be adjusted vertically of the device. These nozzles are provided with longitudinally extending slots 199 through which the exhaust air from the compressor may be directed 125 130

upon the sheets 14. At the forward end of the table, suitable means are provided for precluding shifting of the sheets 14. Such means may comprise an upwardly extending 5 bar or abutment block 99. It should be noted that a Y connects hose 100 and 101 with the pipe 55, which hose in turn are connected with the nozzles 97 and 98. By providing a Y structure, an even distribution 10 of pressure from said nozzles is effected.

The duct extending between the mouth 75 and the port 83 may be provided with a small vent 105 for effecting a reduction of 15 the vacuum operative upon the upper sheet, when the nozzle 66 is first brought into engagement with the stack 14.

The operation of my device is as follows: A stack of sheets 14 is placed upon the table 20 13 and is confined between the safety stop 90 and the block 99. The hand wheel 17 is then actuated to bring the stack of papers to the proper level. Should the motor be started, the cam would then actuate the nozzle 25 66 for bringing same downwardly into engagement with the uppermost sheet and for sealing the port 60. This movement would be about the shaft 70 as the axis. The communication of one of the ports in 30 the nozzle 66 with the hose 65 would cause air pressure to affix the upper sheet of paper to the curved lower face 102 of the nozzle. The parts are so related that, altho, at this time the port 60 is covered, the mouth 75 engages 35 the upper sheet, and the vent 105 permits only enough air pressure or suction to operate upon the upper sheet that the upper sheet only is held by the nozzle 66. The shaft 70 is then actuated through the cam 41 for elevating the shaft 67. Whereas the shaft 67 is below the plane of the horizontal diameter of the shaft 70, this raising motion of the shaft 67 serves to move the upper sheet of paper toward the forward end, or 45 front of the device, thereby throwing an upward bulge or bend into the upper sheet of paper, which serves to separate the upper sheet of paper from the sheet below. During this time the exhaust air from the nozzles 50 97 and 98 is blowing upon the stack 14 and as soon as the slight upward bulge is developed in the upper sheet, this air rushes under the upper sheet and separates same throughout its under area from the sheet 55 next below. The movement of the oscillating nozzle 66 in opposite directions while holding a sheet of paper, serves to throw a wave into the sheet held by the nozzle, said wave moving throughout the sheet and accomplishing the same result as is attained 60 by a pressman when manually feeding large sheets of paper. A pressman when feeding large sheets of paper will grasp the uppermost sheet and will quickly raise and lower his hand while holding the sheet of paper 65

thereby causing a wave to pass throughout the sheet of paper. This is ordinarily and generally referred to as "winding" the sheet and serves to detach the sheet grasped by the pressman, from the sheet next below. 70 Unless the sheet is wended it is practically impossible for the pressman to move the sheet to be fed from the stack of sheets to the mechanisms that receive the sheets from the pressman's hand. The structures 75 disclosed herein and their co-operation is such that there is attained by mechanical means this same winding action utilized by a pressman for separating the uppermost sheet of paper from the stack. The next action 80 resultant from the cam is the counter clockwise movement of the nozzle 66 (see Figs. 2 and 6) whereby to bring other of the ports of the nozzle 66 into communication with the pipe 52 for causing other of the mouths 85 at the curved face 102 of the nozzle to grasp the upper sheet for precluding said upper sheet from settling back upon the stack. As the succeeding mouths 76, 77 and 78 engage the sheet, a greater vacuum operates 90 on the sheet for holding same. The movement of the nozzle 66 is continued until the end of the upper sheet toward the rear of the machine, is passed between rollers 91 and 92, whereupon the sheet is fed from 95 my device by said rollers 91 and 92 and the extension 63 actuates shutter 57 for opening port 60 and releasing the sheet from the nozzle. Attention is called to the fact that at the time when the nozzle 66 moves in said 100 counter clockwise direction, the nozzle has been raised sufficiently high that the end of the upper sheet toward the rear of the device, is raised upwardly beyond the lower edge of the inclined upper end 104 of the 105 safety stop 90. After the upper sheet has been lifted from the sheet next below, greater air pressure is brought into play for retaining the upper sheet in engagement upon the face 102 of the nozzle 66, thereby 110 precluding separation of said sheet from the nozzle. It should be noted that the original suction employed is weak to preclude the picking up of a plurality of 115 sheets.

After the nozzle has fed the upper sheet of paper to the rollers 91 and 92, the suction is cut off, as previously explained. For bringing the nozzle into position for feeding the second sheet, the cycle is such that 120 the oscillation of the cam 41 returns the parts to position for repeating the described action. As the arm 31 is oscillated about its pivotal mounting 32, the ratchet mechanism is actuated for automatically advancing or lifting the stack of sheets 14. After the stack of sheets are elevated to such extent that the link 30 continues to reciprocate without bringing the ratchet mechanism into play, the further advancing or 125 130

raising of stack 14 is checked. As soon as the stack level has fallen sufficiently to permit the finger 36 to move from below the weight 27, the ratchet mechanism is again brought into play for advancing the table 13.

When devices embodying my invention are to be employed with folders, presses and similar machines, the crank shaft 51 may be disconnected from the crank 50 and may be connected with such folders, presses and similar machines, whereby the feeder will operate in synchronism with such other machine. The motor would continue to operate in order to provide the necessary draft and vacuum, as well as for actuating the rollers 91 and 92. In this regard it is pointed out that whereas all of the mechanisms are operated from a single cam, there is no opportunity for the various mechanisms to be moved out of synchronized relationship.

The valve 64 is actuated for attaining the desired suction in view of the nature of the sheets to be fed. For example, with tissue sheets, the valve 64 may be opened to its limit, while with heavy cardboard sheets the valve would be closed.

What I claim is:

1. In a feeder of the class described, the combination of oscillating means for picking up a sheet, for moving the sheet in one direction and then advancing the sheet in an opposite direction longitudinally of the picked up sheet for forming an undulation in the picked up sheet and causing said undulation to move longitudinally of the sheet, and means for receiving the advanced sheet from the oscillating means, and for carrying the sheet from the oscillating means.

2. A feeder device of the class described comprising means for supporting a stack of sheets, means for picking up a sheet from the stack of sheets, for moving the picked up sheet in a given direction for positively separating the picked up sheet from the sheet next below, and for then moving said sheet in the opposite direction longitudinally of the sheet for creating an undulation in the sheet and causing said undulation to move longitudinally of said sheet for separating the picked up sheet from the stack.

3. A feeder of the class described comprising a table for supporting a stack of sheets, abutment means disposed at opposite ends of the sheets and extending above the upper level of the stack of sheets, and means for removing sheets from the top of the stack and comprising a nozzle for picking up the upper sheet, for moving the picked up sheet toward one of said abutments for forming a loop or fold in said picked up sheet and for then carrying the picked up sheet in the opposite direction over the second abutment and causing the

loop to move from the picked up end of the sheet to the end of the sheet disposed adjacent said first abutment.

4. A feeder of the class described comprising a table for supporting a stack of sheets, abutment means disposed at opposite ends of the sheets and extending above the upper level of the stack of sheets, means for removing sheets from the top of the stack and comprising a nozzle for picking up the upper sheet, for moving the picked up sheet against one of said abutments for forming a loop or fold in said picked up sheet and for then carrying the picked up sheet in the opposite direction over the second abutment for causing the loop to move from the end thereof adjacent the first mentioned abutment to the end thereof disposed adjacent the second abutment, and means for directing air under pressure below the fold or loop developed in the upper sheet for separating the upper sheet from the sheet next below.

5. In a feeder of the class described, the combination of means for supporting a stack of sheets to be fed, a sheet feeding means comprising a suction nozzle mounted for oscillation about two distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle in a given direction and means for actuating the nozzle about the first axis for moving said sheet in the opposite direction.

6. In a feeder of the class described, the combination of means for supporting a stack of sheets to be fed, an abutment means for engaging one end of the stack of sheets supported by said stack supporting means, a sheet feeding means comprising a suction nozzle mounted for oscillation about two distinct and spaced axes, means for moving the nozzle relatively to said axis for bringing the nozzle into engagement with the top of the stack of sheets and for disposing one axis in an horizontal plane below the second axis, means for moving the nozzle about the second axis and raising the first axis, whereby to move a sheet carried by the nozzle in a given direction and means for actuating the nozzle about the first axis for moving said sheet in the opposite direction above the abutment means.

7. In a feeder of the class described, the combination of means for supporting a stack of sheets to be fed, an abutment means for engaging the opposite ends of the stack of sheets supported by said stack supporting means, a sheet feeding means comprising a suction nozzle mounted for oscillation about

- two distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle against one abutment means for forming a fold or loop in said picked up sheet, and means for actuating the nozzle about the first axis for moving said sheet in the opposite direction above the other abutment means.
15. 8. In a feeder of the class described, the combination of means for supporting a stack of sheets to be fed, abutment means for engaging opposite ends of the stack of sheets supported by said stack supporting means, a sheet feeding means comprising a suction nozzle mounted for oscillation about two distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle against one abutment means for forming a fold or loop in said picked up sheet, means for actuating the nozzle about the first axis for moving said sheet in the opposite direction above the other abutment means, and means for directing air under pressure beneath the loop formed in the picked up sheet.
9. In a feeder of the class described, the combination of means for supporting a stack of sheets to be fed, abutment means at the opposite ends of the stack of sheets, a suction nozzle mounted for movement about two distinct, spaced and relatively fixed axes, means for moving the nozzle about the first of said axes for bringing the nozzle into engagement with the top of the stack of sheets, and for disposing said first axis in a horizontal plane below the second axis, means for moving the nozzle and the first axis about the second axis whereby to move a sheet carried by the nozzle from the top of a stack of sheets against one of said abutments for forming a loop or fold in said picked up sheet and means for actuating the nozzle about the first axis for moving the sheet in the opposite direction and over the second abutment, an automatic means for advancing the stack of sheets to the nozzle, and means for directing air under pressure below the fold formed in the picked up sheet.
40. 10. In a feeder of the class described, the combination of means for supporting a stack of sheets to be fed, abutment means at the opposite ends of the stack of sheets, a suction nozzle mounted for oscillation about two distinct and spaced axes, means for moving the nozzle relatively to said axes for bringing the nozzle into engagement with the top of the stack of sheets, and for disposing one axis in an horizontal plane below the second axis, means for moving the nozzle about the second axis whereby to move a sheet carried by the nozzle from the top of a stack of sheets against one of said abutments for forming a loop or fold in said picked up sheet and means for actuating the nozzle about the first axis for moving the sheet in the opposite direction and over the second abutment.
55. 11. In a feeder of the class described, the combination of means for supporting a stack of sheets to be fed, abutment means at the opposite ends of the stack of sheets, a suction nozzle mounted for movement about two distinct, spaced and relatively fixed axes, means for moving the nozzle about the first of said axes for bringing the nozzle into engagement with the top of the stack of sheets, and for disposing said first axis in a horizontal plane below the second axis, means for moving the nozzle and the first axis about the second axis whereby to move a sheet carried by the nozzle from the top of a stack of sheets against one of said abutments for forming a loop or fold in said picked up sheet, means for actuating the nozzle about the first axis for moving the sheet in the opposite direction and over the second abutment, an automatic means for advancing the stack of sheets to the nozzle, and means for directing air under pressure below the fold formed in the picked up sheet.
12. In a feeder of the class described, the combination of means for supporting a stack of sheets to be fed, sheet feeding means comprising a suction nozzle, mounted for oscillation about two distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle in a given direction, means for actuating the nozzle about the first axis for moving said sheet in the opposite direction, and means for increasing the suction operative through the nozzle upon the picked up sheet, upon movement of the sheet in the second direction.
60. 13. In a feeder of the class described, the combination of means for supporting a stack of sheets to be fed, an abutment means for engaging one end of the stack of sheets supported by said stack supporting means, a sheet feeding means comprising a suction nozzle, mounted for oscillation about two distinct and spaced axes, means for moving the nozzle relatively to said axes for bringing

ing the nozzle into engagement with the top of the stack of sheets and for disposing one axis in an horizontal plane below the second axis, means for moving the nozzle about the 5 second axis and raising the first axis, whereby to move a sheet carried by the nozzle in a given direction and means for actuating the nozzle about the first axis for moving said sheet in the opposite direction above 10 the abutment means, and means for increasing the suction operative through the nozzle upon the picked up sheet upon movement of the sheet in the second direction.

14. In a feeder of the class described, the 15 combination of means for supporting a stack of sheets to be fed, an abutment means for engaging one end of the stack of sheets supported by said stack supporting means, a sheet feeding means comprising a suction 20 nozzle mounted for oscillation about two distinct and spaced axes, means for moving the nozzle relatively to said axes for bringing the nozzle into engagement with the top of the stack of sheets and for disposing one 25 axis in an horizontal plane below the second axis, means for moving the nozzle about the second axis and raising the first axis, whereby to move a sheet carried by the nozzle against the abutment means for forming a 30 fold or loop in said picked up sheet, means for actuating the nozzle about the first axis for moving said sheet in the opposite direction above the abutment means, and means for increasing the suction operative through 35 the nozzle upon the picked up sheet upon movement of the sheet in the second direction.

15. In a feeder of the class described, the 40 combination of means for supporting a stack of sheets to be fed, abutment means for engaging opposite ends of the stack of sheets supported by said stack supporting means, a sheet feeding means comprising a suction 45 nozzle mounted for oscillation about two distinct and spaced axes, means for moving the nozzle relatively to said axes for bringing the nozzle into engagement with the top of the stack of sheets and for disposing one axis in an horizontal plane below the second 50 axis, means for moving the nozzle about the second axis and raising the first axis, whereby to move a sheet carried by the nozzle against the one abutment means for forming a fold or loop in said picked up sheet, and 55 means for actuating the nozzle about the first axis for moving said sheet in the opposite direction above the other abutment means, means for directing air under pressure beneath the loop formed in the picked up sheet, and means for increasing the suction operative through the nozzle upon the picked up sheet upon 60 movement of the sheet in the second direction.

16. In a feeder of the class described, the 65 combination of means for supporting a stack

of sheets to be fed, abutment means for engaging opposite ends of the stack of sheets supported by said stack supporting means, a sheet feeding means comprising a suction nozzle mounted for oscillation about two 70 distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle against one abutment means for forming a fold or loop in said picked up sheet, and means for actuating the nozzle about the first axis for moving said sheet in the opposite direction above the other abutment means, an automatic means for advancing the stack of sheets to the nozzle, 75 and means for increasing the suction operative through the nozzle upon the picked up sheet upon movement of the sheet in the second direction.

17. In a feeder of the class described, the 80 combination of means for supporting a stack of sheets to be fed, abutment means for engaging opposite ends of the stack of sheets supported by said stack supporting means, a sheet feeding means comprising a suction 85 nozzle mounted for oscillation about two distinct and spaced axes, means for moving the nozzle relatively to said axes for bringing the nozzle into engagement with the top of the stack of sheets and for disposing one axis in an horizontal plane below the second axis, means for moving the nozzle about the second axis and raising the first axis, whereby to move a sheet carried by the nozzle against one abutment means for forming a fold or loop in said picked up sheet, and means for actuating the nozzle about the first axis for moving said sheet in the opposite direction above the other abutment means, an automatic means for advancing the stack of sheets to the nozzle, 90 and means for increasing the suction operative through the nozzle upon the picked up sheet upon movement of the sheet in the second direction.

18. In a feeder the combination of a suction nozzle for moving sheets in opposite directions, and means for creating variable suction within the nozzle determined by the direction of movement of the nozzle.

19. In a feeder the combination of a suction nozzle for moving sheets, means for moving the nozzle in opposite directions, and means for producing a variation in suction in the nozzle when moving in opposite directions.

In testimony whereof, I have hereunto subscribed my name this 26th day of November, 1923.

LESTER K. ALDRICH.
